UNITED STATES PATENT OFFICE.

JOSEPH SYLVESTER URBAN, OF INDIANAPOLIS, INDIANA, ASSIGNOR
OF ONE-HALF TO ANDREW EDWARD NIEBLING, OF INDIANAPOLIS,
INDIANA.

AUTOMATIC IGNITER FOR MATCH-BOXES.

No. 811,458.

Specification of Letters Patent.

Patented Jan. 30, 1906.

Application filed June 20, 1905. Serial No. 266,114.

To all whom it may concern:

Be it known that I, JOSEPH SYLVESTER URBAN, a citizen of the United States, and a resident of Indianapolis, in the county of Marion and State of Indiana, have made a certain new and useful Invention in Automatic Igniters for Match-Boxes; and I declare the following to be a full, clear, and exact description of the same, such as will enable others skilled in the art to which it appertains to make and use the invention, reference being had to the accompanying drawings, and to letters of reference marked thereon, which form a part of this specification.

Figure 1 is a perspective view of a match-box having my invention applied thereto. Fig. 2 is a central longitudinal section of the same, showing the igniter branch sprung back out of igniting position in dotted lines. Fig. 3 is a detail perspective view of the igniter attachment. Fig. 4 is a view similar to Fig. 2, but showing the igniter attachment acting as the spring for the box-cover, with the box-cover open and the igniter branch *d* sprung back out of igniting position. Figs. 5 and 6 are detail fragmentary sectional views showing a modified form of the invention. Fig. 7 shows the box in fragmentary detail view as modified for the form of the invention shown in Figs. 5 and 6.

The invention has relation to an igniter attachment for match-boxes; and it consists in the novel construction and combinations of parts, as hereinafter set forth.

In the accompanying drawings, illustrating the invention, the letter *a* designates a match-box of the usual pocket form, being flattened from side to side and having the cover at one end. *b* represents the igniter attachment, which consists of a deeply-bowed strip of narrow spring metal having a branch *c* and a branch *d* which is usually longer than the branch *c*. The branch *c* is provided at its end with an outward-projecting lug or catch *e* and the branch *d* with a notched press-lug *g*, which also projects outward. The branch *d* is straight and is designed when in use in the match-box to extend along the front or narrow side wall thereof, its press-lug *g* projecting through a rounded opening *h* made through such wall of said box. The branches

of this *U*-shaped attachment diverge normally a little, their lower portions being wider apart than the width of the box, so that when the attachment is placed therein the tension of the branches will cause them to press outward against the narrow side walls of the box. In this manner the lugs of the front and rear branches are caused to engage by spring-pressure the small openings *h* and *k* of the box, these openings being, respectively, in the narrow side walls thereof. The bottom of the box adjacent to one narrow side wall is provided with an opening *m* of sufficient diameter to permit the passage of a match. The lower end *t* of the long branch *d* of the attachment is designed to engage this opening when the attachment is in position in the box. This lower end *t* is serrated on the inside, as indicated at *s*. The notch of the press-lug *g* of this branch is made at about the middle of the lug on its under side, and when it is disengaged from the margin of the opening *h* in the front wall of the box the tension of the spring attachment presses the end *t* of this branch outward against the outer margin of the opening *m*, so that this opening is clear sufficiently to allow one of the matches to protrude therethrough by its lower end. Then the press-lug *g* being operated to engage its notch with the wall of the opening *h* the serrated end of the branch *d* of the attachment is pressed inward and held toward the middle of the opening *m* in position to engage and ignite the head of the match when quickly pulled out of the box through the latter opening.

The attachment can be readily fitted to a pocket match-box in a few moments. It can be removed to allow matches to be placed in the box and then placed in position; but the spring which extends between and has a spring engagement with opposite narrow sides of the box is narrow, being of less width than the width of the box or the distance between opposite long sides of the box, and matches may be placed in the box without moving the attachment. Should it be desired to make the igniter a permanent part of the match-box, the short branch may be permanently secured to the back wall of the box and may serve as the opening-spring for the cover. When the box is charged with matches, it is not necessary to open the cover in order to

get a match, as they are designed to be taken out through the opening in the bottom of the box.

In Figs. 5, 6, and 7 of the invention is shown 5 a modification wherein the top of the box is held in position by the igniter attachment and is separable from the box upon the removal of the igniter attachment. In this form the box has seats x , wherein fit the journals y of the box-top, which are formed at the sides of the lug z , which bears against the spring igniter attachment for the purpose of opening the top and to keep it closed. In 10 these figures a different form of igniter attachment is also shown, wherein the short branch c is free and has an indented end portion c' , terminating in a hook c^2 . In operation the lug z is received and held from displacement in said indented end portion c' when the cover 15 is closed, the spring igniter attachment being at the same time pressed rearwardly or put under tension. The hook c^2 prevents the disengagement of the lug z from the igniter attachment. 20 Having described the invention, what I claim, and desire to secure by Letters Patent, 25 is—

1. The combination with a match-box having an opening in its bottom, of a narrow 30 bent-spring igniter attachment having a spring engagement with opposite narrow side walls of the box, one branch of said igniter attachment having a serrated end portion adapted to engage the opening in the bottom 35 of the box, substantially as specified.
2. The combination with a match-box having a small opening in its bottom near one narrow side wall, of a narrow bent-spring igniter attachment having divergent branches having 40 a spring engagement with opposite narrow side walls of the box, one branch of said attachment having a serrated end portion adapted to engage the opening in the bottom of the box, substantially as specified.
- 45 3. The combination with a match-box having an opening in its bottom, of a narrow bent-spring igniter attachment having its

bend at the top of the box and provided with a branch engaging a narrow side wall of the box and having a serrated end portion adapted to engage the opening in the bottom of the box, substantially as specified. 50

4. The combination with a match-box having an opening in its bottom and an opening in a narrow side wall thereof, of a narrow 55 bent-spring igniter attachment having its bend at the top of the box, one branch of said attachment having a press-lug engaging the opening in the side wall of the box, said branch having a serrated end portion adapted 60 to engage the opening in the bottom of the box, substantially as specified.

5. The combination with a match-box having an opening in its bottom, of a narrow 65 bent-spring igniter attachment having its bend at the top of the box, one branch of said attachment engaging a narrow side wall of the box and having a serrated end portion adapted to engage the opening in the bottom of the box, the other branch of said attachment 70 being adapted to engage a lug of the cover to open and close the same and hold it in place, substantially as specified.

6. The combination with a match-box having a removable cover, of a spring igniter attachment having a long igniter branch provided with a serrated end portion, and a short spring branch engaging a lug of said cover, and adapted to open and close the same and to hold it in place, substantially as specified. 75

7. The combination with a match-box, having the body thereof provided with open journal-seats, and a separable cover having a lug provided with lateral journal extensions fitting in said seats, of an igniter attachment 80 having a spring-arm engaging the lug of the cover, substantially as specified.

In testimony whereof I affix my signature in presence of two witnesses.

JOSEPH SYLVESTER URBAN.
